GARDNER T. VOORHEES, OF NEW YORK, N. Y.

ICE-MAKING PROCESS.

1,321,954.

Specification of Letters Patent. Patented Nov. 18, 1919.

Application filed September 24, 1917. Serial No. 193,037.

To all whom it may concern:

Be it known that I, GARDNER TUFTS VOORHEES, a citizen of the United States, residing at New York city, in the county of New York, State of New York, have invented certain new and useful Improvements in Ice-Making Processes, of which the following is a specification.

My invention relates to improvements in 10 ice making processes in which ice is frozen from a freezing surface to ice previously frozen, to thereby reduce the time for freezing a cake of ice of a given thickness with a freezing medium of a given temperature, or 15 to freeze such a cake of ice in the same time with a hotter freezing medium.

My invention relates to ice frozen in movable or fixed molds or cans, or to ice frozen under this process in any other desired way. 20 I attain these objects by apparatus illustrated in the accompanying drawing in which:—

Figure 1 is a diagrammatic cross sectional view of an ice making tank on line C D of 25 Fig. 2. Fig. 2 is a diagrammatic longitudinal sectional view of said ice making tank of part of Fig. 1 taken on line A B just below the top of the ice of Fig. 1. Fig. 3 is a block of ice. Fig. 4 is the block of ice of Fig. 3 cut apart on the dotted line of Fig. 3, thereby forming two ice blocks A A. Fig. 5 is a diagrammatic longitudinal sectional view of the ice making cans of Fig. 2 and the brine surrounding them, showing different ice 30 formation than that of Fig. 2. Figs. 6 and 7 are longitudinal sectional views of a can with an inverted ice block therein having centering means therefor. Fig. 8 is a longitudinal sectional view of ice making cans 40 and brine surrounding them having two different sizes of cans but with somewhat similar ice formations therein as was shown in Fig. 5. Fig. 9 is a plan view of a can with centering means for an inverted block 45 of ice therein and Fig. 10 is a longitudinal sectional view of Fig. 9 taken on line J K of Fig. 9.

In Fig. 1, 1 is a tank, 2 insulation therefor, 3 can covers, 4 can cover supports, 5^a, 5^b, 5^c, 5^d cans, 6 refrigerating coils, 7 brine, 8 water, 9 ice, 10 a header connecting the upper ends of coil 6, 11 a header connecting the lower ends of coil 6, 12 refrigerant vapor compressing means, 13 compressed refrigerating vapor condensing means, 14 expansion

valve, 15, 19, and 20 pipes, 16 a propeller having a shaft 17 actuated by a motor 18.

Similar lettering applies to Fig. 2.

In Fig. 5, 5^e, 5^f, 5^g, 5^h are cans similar to those shown in Fig. 2. In Fig. 8 cans 5ⁱ 60 and 5^j are similar to the cans of Fig. 2, cans 5^j and 5^k are smaller than the cans 5ⁱ and 5^j.

The ordinary method of ice making is shown in Figs. 1 and 2 wherein a liquefied refrigerant flows from condensing means 13 65 through pipe 20 to expansion valve 14 and therefrom through header 11 and up through coils 6, 6 wherein it is vaporized, the vapor resulting therefrom flowing out of the upper ends of coils 6, 6 through 70 header 10, and pipe 19 to compressing means 12 whereby it is compressed and discharged therefrom through pipe 15 to condensing means 13, wherein it is liquefied, which will be clear to those skilled in the 75 art without a more detailed description. The refrigerant liquid vaporizing in coils 6, 6 cools the brine 7 surrounding them. This brine may be agitated by a propeller 16 actuated by a motor 18 through a shaft 80 17. This cold brine 7 surrounds the cans 5^a, 5^b, 5^c, 5^d thereby cooling the water therein and freezing it into ice 9. Various stages of this freezing are shown where can 5^a has just been filled with water 8 and where can 5^b has had a little ice 9 formed therein and where can 5^c shows said ice 9 somewhat thicker and where said ice 9 has frozen together from both sides on the dotted line in can 5^d. 85

Let us assume that Fig. 3 is an ice block that would have been formed in one of the cans of Figs. 1 and 2. This ice block is shown as if it had right angled corners and paralleled sides but in actual practice it has 95 its sides tapering toward its bottom. This block of ice of Fig. 3 has its thinnest thickness α .

I have found from experience and experiments that with water at 32° F. and with 100 a given temperature of brine that the time required to form an ice block like Fig. 3 will be proportional to $(\alpha/2)^2$. In other words the proportionate time required to freeze such an ice block would be, for a 105 given temperature of brine, starting with water at 32° F. proportional to the square of $\frac{1}{2}$ of its thinnest thickness. I have also found that with a given temperature of freezing surface that ice freezes, from one 110

side only, in a time almost exactly proportional to the square of the thickness. For example, 4 inch ice requires 4 times as long to freeze as does two inch ice. I have also found that a given thickness of ice freezes, from one side only, in almost exactly the ratio of 32 minus the temperature of the freezing surface. So ice of a given thickness would freeze twice as fast with a 12° freezing surface as with a 22° freezing surface. From the above, the relative time of freezing, or relative production of ice, can be found for any temperature of brine or for any thickness of ice or for their combination.

15 For example, if the thickness of b_1 , of Fig. 2 were 1 inch and if the thickness of b_2 were 3 inch and if the thickness of b_3 were 6 inch then the relative times to have frozen these thicknesses of ice; b_1 , b_2 , b_3 20 would be as (1)², (3)², (6)² or as 1, 9, 36.

Now let thickness b_3 equal $a/2$ of Fig. 3 and let thickness b_2 equal $\frac{1}{2}$ of b_3 . We saw from the above that b_2 required 9 units of time to freeze while b_3 required 36 units of time to freeze or that b_3 required 4 times as long to freeze as did b_2 .

Now let us assume that we have 2 blocks of ice as would be formed in the cans of Fig. 2. Let us take these 2 blocks of ice and cut 30 each of them, by any desired means, as was done in Fig. 3, thereby having 4 blocks of ice each like A of Fig. 4. Now take these 4 blocks of ice A and place one of them centrally in each of the cans in Fig. 5. Surround each of these blocks with water 8 and freeze the surrounding water 8 by brine 7 as shown progressively in cans 5^a, 5^b, 5^c, 5^d of Fig. 5. When this is finished, harvest the ice from the 4 cans and cut 2 of the finished 40 cakes as those from cans 5^a and 5^b on lines E F and G H similarly as we cut the ice cake in Fig. 3, place each of these half blocks of ice in one of the 4 cans and repeat as often as desired.

45 Now although we have had no more cans in Fig. 5 than we had in Fig. 2, and no colder brine, yet we have decreased the freezing time required in each of these 4 cans by one half when in Fig. 5, thickness $b = \frac{1}{2}$ of 50 thickness c . Or with same temperature of brine and same cans we could freeze twice as much ice. Or we could freeze as much ice with brine at 22° as with brine at 12°, the old way.

55 In Fig. 8, we could substitute two smaller cans as 5ⁱ and 5^k for the larger can 5^f of Fig. 5 and could freeze the water to ice as is progressively shown, first in these smaller cans, and then place the ice blocks formed therein, 60 one each, in cans 5ⁱ and 5^k, and with the same temperature of brine we could, when $b = \frac{1}{2} c$, freeze 2.67 times as much ice as was done the old way in Fig. 5 in cans 5^a, 5^b, 5^c, occupying the same tank space as do cans 5ⁱ, 5^j, 5^k, 65 of Fig. 8, or could freeze the same quantity of

ice as was done with the three old cans, with 12° brine, the old way, with 24.5° brine, in Fig. 8, in the same time.

In actual practice the cans taper from the top to the bottom, this taper is somewhat exaggerated in Figs. 6 and 7. It is necessary to have this taper in the ice can 5 so that after thawing the ice it may be readily removed from the can and so that in freezing, the water will have a chance to expand 75 without being entrapped, so as to prevent bursting of cans. In Figs. 6 and 7, $\frac{1}{2}$ of a large ice block, cut similarly to that of Fig. 3, has been provided with guide holes h and g , so that it can be centered in can 5 by projections g and by screw f through piece e fitted into can holes at d , d in can 5.

80 Another method of centering an inverted block of ice which might have come from can 5^k of Fig. 8 in a can like can 5ⁱ of Fig. 8 is shown in Figs. 9 and 10 where two removable guides are made by fixing angles i and j together as is shown by separating pieces k . By freezing a little ice as is shown in the lower part of Fig. 10 the block of ice 90 will be held centrally so that the centering angles and separators can then be removed so that the balance of the can can be filled with water and the freezing completed.

90 I prefer to have an upwardly tapering 95 water space between the faces of the ice slab and the walls of the can as is shown in Fig. 10, to obviate a tendency that sometimes occurs, of bursting, or deforming a can, when water is entrapped below ice frozen over it. But I can freeze by this process so that the 100 bursting or deforming of a can does not often occur, even if this precaution is not so taken.

105 It will be clear to those skilled in the art, without further figures or descriptions that when cans in tanks are not movable, that the ice may be thawed loose by heating the brine by high pressure ammonia in the freezing coil or by any other desired way. If the cans are movable then they may be lifted from the brine by the ordinary hoists and moved to an ordinary thawing apparatus and that 110 there the ice cake is thawed from can and removed from it in the ordinary manner and that an ice cake may be split into two or more slabs by a saw or any other desired means and a slab replaced in the can and the can returned to the brine bath by the hoist in the ordinary manner and water put 115 into the can in the ordinary manner by an ordinary can filling hose its quantity being regulated in any desired manner.

120 It is well known that the capacity and economy of a refrigerating machine increases as its suction pressure is higher and that the higher the suction pressure the higher will be the brine temperature. So it 125 will be evident that by the use of this invention the same quantity of ice could be 130

made with a given can space for a higher temperature of brine and therefore for a higher suction pressure and therefore for increased capacity and economy of the refrigerating machine.

The ice that is formed by this process may be what is known as raw water ice or what is known as distilled water ice. The ice so formed may be formed with or without air or other agitation. The part of the ice first frozen may be raw or distilled water ice and the part of the ice secondly frozen may be raw or distilled water ice. The final blocks of ice may be all raw water or all distilled water ice or may have their inner parts or their outer parts distilled water or raw water ice. It is evident that the water deficiency of a distilled water ice making system might be made up by having distilled water centers or outsides and raw water outsides or centers.

The cans in the tanks may be movable or fixed and may be surrounded by brine or any other cooling means, the refrigerating coil 6, 6 may be all inside the tank or partly inside the tank and partly outside or all outside the tank and the circulation of the brine may be all inside the tank or partly inside and partly outside the tank. Any desired means of centering or placing the frozen

blocks in the cans may be used and any desired shape of can or block may be used, all without departing from the process of this invention.

I believe I am entitled to claim this process in the broadest possible manner.

I claim—

1. A process of making and harvesting a built up ice cake in a container, which consists in inserting water and an ice slab in said container, then subjecting the outside of the container to freezing means until a built up ice cake is formed therein and then removing the built up ice cake from the container in a direction reversed to that in which the ice slab was inserted.

2. A process of making ice which consists of placing a slab of ice in a container in such manner that a layer of water surrounding the ice slab will be widest at the top and tapering to the bottom and then applying a freezing medium to the walls of the container until the water enveloping the ice slab is frozen to the walls of the container and to the ice slab.
